[57] CLAIM

The ornamental design for a cable connector interface, as shown and described.

DESCRIPTION

FIG. 1 is a top perspective view of a cable interface in accordance with our design, a body of a connector and insulation displacement pins being shown in broken lines for illustrative purposes only;

FIG. 2 is a right side view thereof, showing a longitudinal profile of the interface;

FIG. 3 is a left side view thereof, this view being a mirror image of the profile illustrated in FIG. 2; and,

FIG. 4 is a top plan view thereof.

The broken lines throughout the drawing views are included for the purpose of illustrating environmental structure only and form no part of the claimed design.
